QUARTER LINING INKING MACHINE

John D. Hossfeld, Beverly, Mass., assignor to
 United Shoe Machinery Company, Borough of
 Flemington, N. J., a corporation of New Jersey

Application December 6, 1939, Serial No. 307,874

10 Claims. (Cl. 91—50)

This invention relates to a machine for applying ink to parts of shoes and is herein shown as embodied in a machine for inking the top margin of an unattached quarter lining.

In the more expensive type of shoe where workmanship and appearance are paramount, it is desirable to stain the edge of the lining which would otherwise be noticeable when viewing the top edge of the upper of a finished shoe because of the fact that it is generally of a different color than the upper. While this can be done with a brush after the shoe is completed, the better way is to apply the stain, hereinafter called ink, to the margin of the lining prior to the assembly so as to avoid soiling the upper and the inner or display surface of the lining. By permitting the ink on the margin to partly penetrate the work, a large portion of the edge surface will be stained, as explained in United States Letters Patent No. 2,160,878, granted June 6, 1939, on an application filed in the name of D. La Valle. With this method, subsequent trimming of the lining will, nevertheless, leave a stained edge as desired.

An object of the present invention is, therefore, to provide a machine for applying ink to the margin of a lining prior to attaching the same to the upper.

In order to accomplish this end the present machine is provided with an ink-carrying roll and means for feeding the work past the ink-carrying roll with its marginal portion in contact therewith, said means being constructed and arranged simultaneously to bend that portion of the sheet material which is in contact with the surface of the ink roll to stiffen it so that it will bear against the surface and absorb the desired quantity of ink.

In order to permit the work to absorb the proper quantity of ink, it is desirable to hold a substantial length of the work in contact with the peripheral surface of the ink-carrying roll as it passes through the machine. To this end and in accordance with a further feature of the invention a spring finger is arranged to extend widthwise of the surface of the ink-carrying roll to press the work lightly against the surface of the ink-carrying roll at a point removed from the top thereof so as to cause the work to engage the surface of the roll over a substantial arc.

Another feature of the invention comprises a work gage arranged to engage the edge of the work lying across the ink roll to guide the same, the gage being mounted, however, so that it may

be moved away from the surface of the ink roll to permit the passage of an irregularity in the work, such as a strap or button tab, without disturbing the position of the band of ink which is being applied to the marginal portion of the work.

In some cases, particularly when the edge of the lining is quite regular, it is not necessary to apply a wide band of ink to allow for subsequent trimming, and since a substantial saving may be made by applying a narrower band of ink, the above-mentioned gage is preferably so constructed as to be movable from a position substantially at the edge of the ink-carrying roll to a position part way across its surface, whereby only a part of the width of the roll is employed for applying ink.

A machine constituting a preferred embodiment of the invention is shown in the accompanying drawings, in which

Fig. 1 is a side elevation, partly broken away and partly in section;

Fig. 2 is an enlarged view of the scraper for the ink pick-up roll;

Fig. 3 is an end elevation partly broken away and partly in section;

Fig. 4 is an enlarged fragmentary view in side elevation, showing the feed rolls and the ink-carrying roll;

Fig. 5 is an enlarged fragmentary front elevation broken away to show the position of the gage members relative to the ink-carrying roll and the upper feed roll;

Fig. 6 is a plan view of the machine broken away in part;

Fig. 7 is an enlarged view of the gage locking mechanism;

Fig. 8 illustrates a band of ink as applied by the machine to the margin of an unattached lining; and

Fig. 9 illustrates gearing which is used to drive the feed roll of the machine.

The machine of this invention is provided with an ink-carrying roll 10 (Figs. 1, 3 and 4), a pick-up roll 12 (Fig. 3) arranged to dip into an ink tray 14 and to lift ink therefrom to the surface of the roll 10, a pair of feed rolls 16 and 18 adapted to feed the work past the surface of the ink-carrying roll 10, a gage 20 arranged to guide the edge of the work and a spring finger 22 to guide the top of the work.

These elements are illustrated as carried by a frame having a base 24, vertical end walls 26 and 27 and side walls 28, the side walls at the rear 55 of the machine terminating in the end wall 26

short of the end of the base. At the front of the machine, however, the side walls 28 extend forwardly beyond the end wall 27. A hollow casting 30 of such dimensions as to enclose the space on the base of the machine back of the wall 26 is pivoted to the base at 31 and is provided with an arm 32 arranged to overhang the forward part of the frame, the arm being held in a horizontal position by the engagement of surfaces 34 and 36 formed respectively on the under side of the arm and the top of the frame.

It is desirable that the edge of the lining of the shoe top be stained with ink so that it will not contrast with the upper and, since the inking is done prior to the assembly, the inking of the edge must be done in such a way that subsequent trimming will not remove the inked edge. Furthermore, since it is desirable to have the inner or display surface of the lining of a different color than the upper, the ink must not penetrate through to that surface. The ink-carrying roll 10 is, therefore, provided with a knurled surface 38, the amount of ink carried by the surface 38 being governed by the pick-up roll 12, which will be described hereinafter, so that the quantity of ink applied to the work will be sufficient to provide a uniform distribution of ink substantially through the work but will not be sufficient to penetrate entirely through so as to show on the display surface of the lining.

The roll 10 is mounted for rotation on one end of a horizontal shaft 40 which is journaled in bearings formed in the vertical walls 26 and 27, the other end of the shaft having fixed thereto a gear 42 by which it is driven. Preferably thermoplastic ink is employed and, therefore, the ink-carrying roll 10 is heated. As illustrated, a shallow recess 44 (Fig. 4) is formed in a lateral face of the roll 10 and a flat heating element 46 is placed therein, the heating element being fixed by means of a collar 48 and set screw 49 to one end of a sleeve 50 encircling the shaft 40. The other end of the sleeve passes through the wall 27 and constitutes a part of the bearing for the shaft 40. An electrical connection 52 is made at a suitable point (Fig. 3) for energizing the heating element.

The ink is presented to the surface of the ink-carrying roll 10 by the pick-up roll 12 mounted for rotation on a shaft 54 with its upper side in tangential contact with the roll 10 and its lower side dipping beneath the surface of ink in the tray 14. A gear 55 at the rear end of the shaft 54 provides for the rotation thereof.

The ink tray 14 rests on a heating element 56 screwed to the base 24 and may be moved relative to the pick-up roll by means of screws 58. The tray is of sufficient length to lie beneath both the pick-up roll and ink-carrying roll, even though their centers are offset laterally, so that it will catch any excess ink that might drop from their surfaces.

Scrapers are provided to clear the excess ink from the ink rolls and to govern the quantity transferred thereby to the work. To this end the ink roll 10 is provided with a scraper 60 which is mounted on a stud 62 projecting from a plate 64 screwed to the wall 27 and is held in contact with the rear face of the roll 10 by a spring 64 (Fig. 1), the purpose of the scraper being to prevent ink from creeping to the heating element. A similar scraper 66 is provided to prevent ink from creeping over the back surface of the pick-up roll and from subsequently traveling along the shaft to the bearings. Another scraper 68 is

provided to engage the peripheral face of the pick-up roll 12 at the upcoming side thereof so as to govern the quantity of ink thereon. The scraper 68 is fixed at one end to a sleeve 70 (Fig. 3) mounted for axial movement in a bracket 72 screwed to the frame, the opposite end of the sleeve being provided with a flange 74. The sleeve is threaded internally for the reception of a screw 76, the neck of which is journaled in the wall 28 with the head 78 bearing against the outer surface of the wall. Rotation of the screw 76 moves the sleeve in or out, thereby providing for adjustment between the scraper 68 and the roll 12 so that the amount of ink picked up by the roll may be controlled. The scraper 68 is yieldably held in its adjusted position by a coiled spring 80 disposed axially about the neck of the screw 76 between the flange 74 and the inside of the wall 28.

The feed rolls 16 and 18 by which the work is fed to the ink-carrying roll 10 are set off to one side thereof. This is preferable to the use of a single feed roll in combination with an ink roll in wringer fashion because there is a tendency in such a case for the film of ink on the ink roll to accumulate at the bite of the rolls as the work passes through due to the squeezing action of the rolls which hold back some of the ink not absorbed, thereby increasing the quantity of ink at that point. This accumulation is frequently such that when the trailing end of the work passes through the bite of the rolls the ink will bridge the gap between the rolls and coat the upper feed roll. As a result, when the next piece of work is fed through, the display surface thereof will be stained. Since, for the reason assigned, it is desirable to have the feed rolls 16 and 18 grip the work inwardly of the portion presented to the ink roll, some provision must be made to cause the work to bear against the ink roll. In order, therefore, to cause the projecting margin of the work to bear against the surface of the ink roll, the surfaces of these feed rolls are cut at obtuse and acute angles 82 and 84 respectively (Fig. 4) to the surface of the ink roll so as to tilt the edge of the work downwardly toward the ink roll. As a result the marginal portion of the work is deflected by its contact with the surface of the ink roll. This deflection or bending naturally stiffens the margin of the work in the direction of its edge and causes it to bear firmly against the roll 10.

The roll 16 is an idler roll and is mounted on a stud 86 projecting inwardly from a web 85 and is fixed thereto by a nut 87. The roll 18 is driven and is mounted on a shaft 88 which is mounted so that it may be moved to and from the roll 16 to permit introduction of work between the rolls. To this end the shaft 88 is journaled at 92 and 94 in a bracket 90 having a yoke 94 integral therewith. The yoke is pivotally supported between a pair of ears 96 and 98 which are integral with the wall 26. A pair of studs 100 are threaded through the ears 96 and 98, the inner ends of the studs being conical and serving as bearings for supporting the yoke 94. An arm 102 depends from the bracket 90 just forward of the yoke, the end of the arm terminating in a flat bearing surface 104. A bell-crank lever 106 is pivotally mounted in journals 108 extending from the wall 26, one arm of the bell-crank lever being arranged to engage the surface 104 of the arm 102 and the other arm having connected thereto a treadle rod 110 by which the lever 106 may be rotated about its fulcrum so as to tilt the bracket 90 about its

pivot points, thereby to separate the roll 18 from the roll 16. The combined weight of the bracket 90 and roll 18 is depended upon to hold the rolls in contact during the passage of the work between them. A gear 112 is keyed to the end of the shaft 88 and meshes with the gear 42 which in turn meshes with a gear 114 secured to the main shaft 116. The main shaft is journaled at one end in the wall 26 and has on its free end driving and idler pulleys P and P'.

While the feeding rolls direct the work downwardly at an angle to the surface of the ink roll so that the work is bent by contact with the ink roll, thereby imparting a certain amount of stiffness to the marginal portion of the work, it is desirable to increase this somewhat more than can be done by the feed rolls alone and also to cause the work to engage the surface of the ink-carrying roll over a substantial arc so as to permit the work to absorb the necessary quantity of ink. To this end a spring finger 22 is attached to the bracket 90 so that it projects widthwise of the ink-carrying roll (Fig. 4). As shown in Fig. 5, this spring finger lies to one side of the top of the ink-carrying roll so that the work fed into the machine will be pressed into contact with the surface of the ink roll between the spring finger and the bite of the feed rolls. The bending produced by the spring finger also has the effect of stiffening the material and causing it to bear firmly against the ink roll.

In order to provide for the passage of work having an irregularity along its edge, such as a strap or button tab T (Fig. 8), the edge gage 20 is mounted on the end of a spindle 118 so that it may be rotated below the periphery of the ink-carrying roll and thus permit the irregularity to project beyond the inner edge of the roll.

The spindle 118 is journaled at its ends in the walls 26 and 27 and is provided between its ends with an arm 120 to which there is attached a treadle rod 122 by which the spindle may be rotated so as to move the gage 20 downwardly away from the periphery of the ink-carrying roll. The gage 20 is normally maintained in working position by a torsion spring 124 disposed axially of the spindle 118, one end of the spring being fixed to the wall 26 and the other end to the arm 120 so as to urge the spindle in a counterclockwise direction as viewed in Fig. 5.

A saving in the quantity of ink used may be made by applying a narrower band of ink when the lining requires very little trimming. Provision is therefore made to move the gage 20 forwardly over the face of the ink roll 16 so that only a portion of the width of the roll will contact the work. To this end the spindle 118 is mounted so that it may be moved axially by pushing against the face of the gage 20. An arm 126 (Fig. 7) is fixed to the spindle 118 and the free end of the arm is arranged, when the gage is in working position, to lie between a pair of dowel pins 128 and 130 which project from the rear face of the wall 27, the edge of the arm resting against the end of a projecting lug 129. When it is desirable to hold the gage in a position part way across the surface of the ink roll, it is only necessary to push the spindle axially until the arm 126 clears the dowel pin 130 whereupon the spring 124 rotates the spindle so as to bring the arm between the dowel pins 130 and 132. If the endwise pressure is then released, the spring 124 will force the arm to the left, as viewed in Fig. 4, where it will be held between the dowel pins 130 and 132 against the surface of a boss 131.

which lies inwardly of the lug 129 so that the gage 20 will lie part way across the peripheral face of the ink-carrying roll.

The housing 30 at the rear of the machine is locked down by a thumb screw 134 which passes through an aperture in the wall of the housing and is threaded into an ear 135 projecting from the wall 26. To provide a neat looking machine, the front end of the machine is enclosed by a panel 136 pivoted to the end of one of the walls at 138 and arranged to span the open end of the machine.

The drive includes a conventional belt shifter 140 for moving the belt 142 from the loose pulley 15 P' to the driving or fixed pulley P. Rotation of the shaft 116 drives the gear 114 which in turn drives the gears 55, 42 and 112 (Fig. 9).

In operation the roll 18 is lifted from the roll 16 sufficiently to permit the introduction of the work which is pushed along the table S in the direction indicated by the arrow so that its inner edge contacts with the gage 20. The arrangement of the feed rolls produces a semiautomatic feed in that the work will pass through without close attention. However, when the outline is very irregular the operator must guide the work so as to follow the outline of the edge, particularly when the edge includes convex curves. When the work has a strap or button tab projecting from its edge, the operator lowers the gage 20 as the projection passes that point so as to permit the work to pass freely through the machine. If it is desired to apply a narrow band of ink to the marginal portion, the gage 20 may be moved inwardly across the ink-carrying roll and held there so that the edge of the work can be pushed only part way across the surface of the ink roll.

Having described my invention, what I claim as new and desire to secure by Letters Patent of the United States is:

1. In a machine for inking the edge of thin material, an ink-carrying roll, and a pair of feeding rolls mounted on axes parallel to the axis 45 of the ink-carrying roll, said rolls having complementary surfaces sloping toward the surface of the ink-carrying roll constructed and arranged to cause the material adjacent to its edge to be deflected by the ink-carrying roll so as to stiffen 50 that portion of the material while it is in contact with the ink-carrying roll.

2. In a machine for inking the edge of thin material, an ink-carrying roll, a member adjacent to a lateral face of the ink-carrying roll, said member having a surface sloping away from the axis of the ink-carrying roll, and a driven feed roll having a surface coating with the surface of said member whereby that portion of the work adjacent to its marginal portion is held 55 at an angle to the surface of the ink-carrying roll.

3. In a machine for applying ink to the edge of work, an ink-carrying roll, means for feeding the marginal portion of the work past the peripheral surface of the ink roll so as to absorb ink therefrom, a gage for engaging the edge of the work, the work-engaging surface of said gage being normal to the peripheral surface of the ink-carrying roll, and means for moving the gage in the plane of its work-engaging surface away from the peripheral surface of the ink-carrying roll.

4. In a machine for applying ink to the edge of work, an ink-carrying roll, means for feeding the marginal portion of the work past the pe-

riperipheral surface of the ink roll so as to absorb ink therefrom, a gage having a work engaging surface normal to and projecting above the peripheral surface of the ink roll, means to hold the gage in that position, and means to move it below said surface of the ink-carrying roll.

5. In a machine for applying ink to the edge of work, an ink-carrying roll, means for feeding the marginal portion of the work past the peripheral surface of the ink roll so as to absorb ink therefrom, a gage for engaging the edge of the work lying across the ink roll, a spindle rotatably supporting the gage, and means for rotating the spindle to move the gage away from the peripheral surface of the ink roll.

6. In a machine for applying ink to the edge of work, an ink-carrying roll, means for feeding the edge of the work past the ink-carrying roll to cause the material to absorb ink therefrom, a two-position gage movable from a position at the edge of the ink-carrying roll to a position part way across the surface of the roll, means for holding the gage in the first position, and a spring for urging the gage into the second position, said gage being movable into a position in which the spring operates to move the gage from the first position to the second position.

7. In a machine for applying ink to the edge of work, an ink-carrying roll, means for feeding the edge of the work past the ink-carrying roll to cause the material to absorb ink therefrom, a two-position gage movable from a position at the edge of the ink-carrying roll to a position part way across the surface of the same, a spindle for supporting the gage, means associated with the spindle constructed and arranged to urge the spindle to move axially and to tend to rotate the same, a lug arranged to prevent axial movement, and a pin to prevent rotational movement, the spindle being movable axially to 40

render the lug and pin inoperative whereupon said last-named means rotates the spindle into a position in which it moves the same axially to move the gage into the second position.

8. In a machine for inking the edge of thin material, an ink-carrying roll, means adjacent to a lateral face of the ink-carrying roll for feeding the marginal portion of the material past the surface of the ink-carrying roll, said means being constructed and arranged simultaneously to bend the material longitudinally so as to stiffen that portion of the material in contact with the ink-carrying roll, and means disposed opposite the peripheral surface of the ink-carrying roll to bend the material transversely of its edge so as to increase the stiffness of the material.

9. In a machine for inking the edge of thin material, an ink-carrying roll, means for feeding the marginal edge of the material past the surface of the ink-carrying roll and for simultaneously bending the material longitudinally so as to stiffen that portion of the material in contact with the ink-carrying roll, and a member arranged to engage the top of the material at a point on the ink-carrying roll removed from the top thereof to cause said material to engage the surface of the roll over a substantial arc thereof.

10. In a machine for inking the edge of thin material, an ink-carrying roll, means for feeding the marginal portion of the material past the surface of the ink-carrying roll and for simultaneously bending the material longitudinally so as to stiffen that portion of the material in contact with the ink-carrying roll, and a spring finger arranged to extend widthwise of the surface of the ink-carrying roll and removed from the top thereof to engage the top of the material and cause the same to engage the surface of the roll over a substantial arc.

JOHN D. HOSSFELD.
